UNITED STATES PATENT OFFICE.

JOHN IRVING AND ALBERT JAMES RISON, OF WANGANUI, WELLINGTON, NEW ZEALAND.

STAMP AND METHOD OF MAKING SAME.

Application filed May 20, 1922. Serial No. 562,547.

To all whom it may concern:

Be it known that we, JOHN IRVING and ALBERT JAMES RISON, both citizens of the Dominion of New Zealand and subjects of the King of Great Britain, and both residing at 3 Anson Street, Wanganui, in the Provincial District of Wellington, New Zealand, have invented an Improved Stamp and Method of Making Same, of which the following is a specification.

This invention relates to that class of stamps whereby letters, numerals or designs are reproduced by means of perforations made in the material or substance to be stamped or marked, and provides a stamp which is of simple construction, and by which a signature, letters, numerals or designs can be accurately, readily and cheaply reproduced, in the form of perforations.

According to the invention the signature or design which is desired to be reproduced, is written or drawn upon a sheet of paper which is then spread and secured upon a sheet of asbestos. The asbestos is placed upon a sheet of glass or other hard substance having a flat surface, and the pins are stuck upright and close together through the signature or design, and through the asbestos sheet until the points come into contact with the glass or other hard substance. By this means the points of the pins are kept level with each other. The upper portions of the pins which project above the asbestos are then secured together and a suitable fence or mould is placed around the edge of the asbestos. Solder, white metal, printer's type metal or the like is then run into the mould so formed and when set forms a solid backing in which the secured together ends of the pins are embedded.

The mould or fence and the asbestos are then removed leaving the pins projecting from the block of metal in the true conformation of the signature or design as first produced on the sheet of paper.

The block is then mounted on a suitable stock or handle.

The invention will be further described with the aid of the accompanying drawing in which:—

Figure 1 shows in perspective a piece of paper, bearing a signature, secured on asbestos and pins inserted in the signature and asbestos to make contact with a sheet of glass beneath the asbestos.

Figure 2 is longitudinal sectional elevation showing some of the pins secured together at their upper ends;

Figure 3 is a cross sectional elevation (broken) showing the fence or mould in position and metal cast on the upper ends of the pins, and Figure 4 is an end elevation of a finished stamp.

A sheet of asbestos 1 of suitable size is placed upon a slightly larger sheet of glass 2 or other hard flat material. A sheet of paper 3 having written or drawn thereon the signature or design 4 which it is desired to reproduce is laid on top of the asbestos sheet 1 and secured thereto by pins 5 or 6 other suitable fastening means.

Pins 6 are inserted upright and close together through the signature or design 4 on the paper 3 and through the asbestos sheet 1 until the points of said pins 6 come into contact with the glass 2.

Pins are placed in this manner over the whole of the signature or design 4.

The upper ends of the pins 6 which project above the asbestos sheet 1 are then secured together, preferably by tinning or soldering as shown at 7 in Figures 2 and 3.

A mould or fence 8 (Figure 3) is now placed around the asbestos sheet 1 as it rests on the glass 2.

Solder, white metal, printer's type metal or the like is then melted and poured into the space enclosed by mould or fence 8, said molten metal surrounding the secured together upper ends of the pins 6 and when set forms a solid block 9 from which the pins 6 rigidly project.

The fence or mould 8, asbestos sheet 1 and glass 2 are now removed leaving the lower ends of the pins 6 projecting downwards from the solid metal backing 9, in true conformation of the signature or design 4.

The metal block 9 is then mounted on a suitable handle or grip 10.

If desired the metal block 9 may be prepared in a form suitable for use in a printing machine or the like, in which case the handle 10 can be dispensed with.

The inking of the pins 6 is effected by means of a pad of cork, this material allowing the pins 6 to enter freely and to be inked above their tips, thereby preventing running of the ink when using the stamp on soft fabrics or the like.

By using pins with blunt ends, or with

lower ends having a diameter equal to their stems, the stamp may be used for printing or stamping without perforating the material to which the stamp is applied.

5. What we do claim and desire to obtain by Letters Patent of the United States of America is:—

1. A method of producing a device of the kind described, comprising inserting pins in 10 an imperforate material to conform to the configuration of a design, securing a backing on the pins, and removing the material in which the pins were inserted.

2. A method of producing a device of the kind described comprising inserting pins in 15 paper and a soft material on which the latter is secured so as to conform to the configuration of a design on the paper, the pin points being kept level with each other 20 securing a backing on the outer ends of the pins, and removing the paper and material in which the pins were inserted.

3. A method of producing a device of the kind described comprising inserting pins 25 in paper and a soft material on which the latter is secured so as to conform to the configuration of a design on the paper and so

that the pin points are kept level with each other securing together the outer ends of the pins; casting a backing on said outer 30 ends, and removing the material in which the pins were inserted.

4. A method according to claim 3 the soft material, being heat resisting.

5. A method of producing a device of the kind described consisting in securing a 35 paper with a design thereon on soft heat resisting material; placing the latter on a hard flat surface; inserting pins in the paper and the soft heat resisting material so that 40 the pin points make contact with said hard flat surface; soldering the other ends of the pins together; moulding a backing on the secured together ends of said pins and removing the material in which the latter 45 were inserted.

In testimony whereof we have signed our names to this specification in the presence of two witnesses.

JOHN IRVING.
ALBERT JAMES RISON.
